GRINDING MACHINE

Clement Booth and Andrew Strom, Cincinnati, Ohio, assignors to Cincinnati Grinders Incorporated, Cincinnati, Ohio, a corporation of Ohio

Application July 3, 1931, Serial No. 548,609

14 Claims. (Cl. 51—103)

This invention relates to improvements in grinding machines and especially to improvements in what are commercially known as centerless grinders.

5 An object of the invention is the provision of an improved grinding machine for grinding formed work pieces.

Another object of the invention is the provision of improved means for presenting and 10 feeding a formed work piece to and through the throat of a centerless grinder.

15 A further object of the invention is the provision of an improved grinding machine for automatically, accurately and expeditiously grinding tapered barrel shaped rolls or similar work pieces having a circular cross section and a convexed surface.

20 A still further and specific object of the invention is the provision of a centerless grinder having formed grinding and regulating wheels cooperating with an improved feeding mechanism for positively feeding the work pieces in an arcuate path through the throat of the centerless grinder to grind tapered convexed rolls to a true 25 circular cross section.

Other objects and advantages of the present 30 invention should be readily apparent by reference to the following specification considered in conjunction with the accompanying drawings and it is to be understood that any modifications may be made in the exact structural details there shown and described, within the scope of the appended claims, without departing from or exceeding the spirit of the invention.

35 In the drawings:

Figure 1 is a front elevation of a centerless grinder embodying the improvements of this invention.

Figure 2 is an enlarged fragmentary illustration 40 of the parts forming the grinding throat with the enclosing housings removed.

Figure 3 is a transverse sectional view through the throat of the device illustrated in Figure 1.

Figure 4 is a sectional view taken substantially 45 on line 4—4 of Figure 2.

Figure 5 is a plan view of the parts as seen substantially from line 5—5 of Figure 4.

Figure 6 is a sectional view taken substantially 50 on line 6—6 of Figure 5.

Figure 7 is a view of the loading mechanism, as seen from line 1—7 of Figure 2.

Figure 8 is a perspective view of the work piece to be operated upon by the machine illustrated in the drawings.

Figure 9 is a fragmentary sectional view illus-

trating the discharge of the work at the end of its travel.

Throughout the several views of the drawings similar reference characters are employed to denote the same or similar parts.

The invention has been illustrated in connection with a standard centerless grinder which machine may comprise a bed 10 having rising therefrom the pedestal bearing 11 for a spindle to which is secured for movement therewith the 10 grinding wheel 12. The bed is further provided on its upper end with ways 13 guiding for movement toward and from the grinding wheel a slide 14 in turn supporting a second slide 15 carrying the housing 16 in which is journaled the 15 spindle 17. Secured to the free end of the spindle 17 is a formed regulating wheel 18 for movement therewith and the spindle has secured to it intermediate its ends a sprocket 19 about which is trained sprocket chain 20 for rotating the said 20 spindle.

The grinding and regulating wheels are spaced from one another to provide a grinding throat therebetween and the said wheels are rotated in a clockwise direction whereby the proximate 25 points of the wheels on opposite sides of the throat travel in opposite directions, the grinding wheel traveling downwardly and the regulating wheel upwardly, as seen in Figure 1. The grinding wheel is rotated at a rapid rate of speed to effect 30 a stock removal from the work while the regulating wheel rotates at a comparatively slower rate of speed for frictionally controlling the rate of rotation of the work.

The slides 14 and 15 are adapted to be shifted 35 relative to one another to adjust the grinding throat to the desired size while the said slides are moved as a unit for effecting an in-feed grinding operation. For this purpose there are provided clamps 21 for securing the lower slide to the bed 40 and a clamp 22 for securing the slides to one another. Movement of the slides is effected through an adjusting screw 23 having threaded engagement with an oscillating nut 24 carried by the housing 16. The screw is mounted at its 45 free end in a bearing 25 secured to an overhanging bracket portion 26 of the bed. A hand wheel 27 is secured to the screw exteriorly of the bearing 25 whereby same may be operated.

In the operation of the machine, as illustrated 50 in the drawings, the grinding and regulating wheels are adjusted to the desired point and locked and the work is automatically fed through the said grinding throat. For this purpose there is secured to the regulating wheel 18 a bevel gear 55

28 meshing with a bevel pinion 29 fast on a shaft 30 journaled in a bracket 31 which is supported as at 31a by the housing 16. The bevel pinion 29 has integral therewith a spur pinion 32 meshing 5 with a spur gear 33 on splined shaft 34 journaled at one end as at 35 in the regulating wheel housing 16. The splined shaft 34 is further journaled in a bearing 34a upstanding from a bracket 39 from which bearing 34a the shaft extends through 10 the bearing hub 36 of a bevel pinion 37 journaled in a bearing 38 carried by bracket 39. The bracket 39 is secured to the base 39a on the forward end of lower slide 14. A bevel gear 40 keyed to a vertical shaft 41 meshes with and derives its 15 power from the bevel pinion 37. The bevel gear 40 has a hub 42 extending therefrom received and journaled in a bushing 43 carried by bracket 39. Secured to the vertical shaft 41 for movement therewith is a spur pinion 44 in turn meshing 20 with a large gear 45 secured to, as by screws or bolts 46, a star wheel or cam 47. A clamp plate 48 received in a recess in the gear 45 clamps the said gear and cam 47 through the agency of a screw 49 to a stud 50 rotatably journaled in the bracket 39. The cam 47 is spaced above the base 39a of the bracket 39 by means of a boss 51 integral with the base 39a so that an arm 52 extending from work rest block 53 may underlie the cam 47.

30 From the foregoing it will be noted that rotation of the gear 45 and cam 47 derives its power from the regulating wheel spindle 17 therefore the rotation of the regulating wheel 18 and cam 47 is synchronized one with the other.

35 The cam 47, as illustrated in Figure 5, has extending from it the arms 54 and receives therebetween a roller 55 carried by the end of the arm 52 through the agency of a screw 56 which extends through the roller into the arm. The work rest block 53 adjacent the arm 52 is provided with a bearing 57 through which a stud 58 passes, the stud being secured in the base 39a and forms the axis about which the block 53 oscillates. A spring 59 is coiled about the stud 58 and has one end 40 secured in the bracket 53 and the other end 60 secured in the base 39a. A lock nut 62 on the end of the stud 58 prevents disassociation of the parts. The block 53 is further provided with a bearing way or groove 63 receiving a track 45 50 54 integral with or secured to the base 39a.

55 As the cam 47 is rotated the arms 54 thereof successively pick up the roller 55 and oscillate the bracket 53 against the resistance of the spring 59 in a clockwise direction, as seen in Figure 6. As the roller passes over the pushing arm the spring 59 returns the bracket 53 to its normal position or oscillates the same in a counter clockwise direction.

60 The bracket 53 carries at its upper end a work rest blade 65 having a seat portion 66 intermediate the lateral side of the blade 65. The face of the seat portion 66 is inclined as at 67 in Figure 4, the direction of inclination being downwardly toward the regulating wheel whereby a work receiving trough is formed between the said inclined face 67 and face of the regulating wheel.

65 As will be noted from Figure 8 the work piece 68 to be operated upon is tapered, the end 69 thereof being of a smaller diameter than the end 70 and the surface adjoining the said ends is convexed as at 71 whereby the greatest diameter is intermediate the ends 69 and 70 being nearer the end 70 than the end 69. For this reason the regulating wheel is provided with a circular track 75 or groove 72 in a spiral form, the tracks being

separated by a rib 73. In order that the work may be uniformly rotated while being operated upon the track 72 is undercut as at 74 to clear the portion of the work including the major diameter so that the regulating wheel contacts 5 at points 75 and 76 adjacent the opposite sides of the cut-away part 74 at points on the work of substantially equal diameter. This construction insures constant uniform rotation of the work about a definite axis. In order to grind 10 the surface 71 of the work the grinding wheel is concaved, as at 77 in Figure 2.

15 Referring now to Figures 2 and 6. The axis of the stud 58 is spaced from the active face 77 of the grinding wheel 12 a distance corresponding to the radius of the surface 71 of the work. Therefore, the work in passing through the grinding throat on the arcuate path determined by the said axis of the stud 58 will have the surface thereof ground to the desired form. This 20 is further insured by the forming of the seat or track 72 in the regulating wheel 18 to conform with the opposite side of the work piece 68.

25 The work is automatically loaded on to the seat portion 66 of the blade 65 for which purpose there is provided a chute 78 down which the work 68 rolls by gravity being prevented from discharge from the chute by a spring loaded latch 79, the latch 79 being pivoted at 80 to the chute 78 and has associated therewith a spring 30 81. A trip arm 82 is associated with the latch 79 and cooperates with a cam surface 83 formed on the work rest blade 65. As best seen in Figure 2, as the work rest blade 65 returns to the loading position the cam 83 rides under the trip 35 arm 82 raising same about its pivot against the resistance of spring 81 and permitting the unfinished work to roll from the chute 78 on the inclined surface 67 of the seat portion 66. As the blade 65 travels through the grinding throat 40 the spring 81 forces downwardly the latch 79 into engagement with the second work piece preventing its discharge from the grinding throat.

45 By reference to Figure 9 it will be noted that the reverse side of the regulating wheel is provided with an undercut circular groove 85. The end of the cam track 72 terminates at the said rear face of the regulating wheel. A discharge chute 86, see Figures 2 and 3, has its inner end placed below this groove 85 and is positioned at 50 a point indicating the rear terminus of the travel of the blade 65. This terminus of travel is beyond the face of the regulating wheel 18 so the work is no longer contacting therewith, therefore, as soon as the work clears the wheel it rolls 55 by gravity down the inclined seat portion 67 into the end of the chute 86 which in turn is so positioned relative to the machine as to carry the finished work to a suitable receptacle.

60 What is claimed is:

1. In a grinding machine for grinding tapered radius rolls the combination of opposed contragenerically formed grinding and regulating wheels having a grinding throat therebetween, the regulating wheel having a spiral track conforming to the periphery of the rolls, and means for positively feeding the work pieces in an arcuate path through the grinding throat while the said work is in simultaneous contact with the face of the grinding wheel and the spiral track 70 of the regulating wheel.

2. In a grinding machine of the class described for grinding tapered barrel shaped rolls the combination of a grinding wheel having an operative face conforming to the periphery of the roll to 75

- be ground, an opposed regulating member having a spiral track and contacting with the roll at two points of equal diameter for controlling the rotation of the rolls, the grinding wheel and regulating member being spaced from one another to form a grinding throat, a work rest within the grinding throat having an inclined seat extending downwardly toward the regulating member for receiving the roll, means for actuating the work and work rest arcuately of the grinding throat, and means for driving the regulating wheel and work rest actuating means in timed sequence. 5
3. In a grinding machine of the class described for grinding tapered barrel shaped rolls the combination of a grinding wheel having an operative face conforming to the periphery of the roll to be ground, an opposed regulating member having a spiral track and contacting with the roll at two points of equal diameter for controlling the rotation of the rolls, the grinding wheel and regulating member being spaced from one another to form a grinding throat, a work rest within the grinding throat having an inclined seat extending downwardly toward the regulating member for receiving the roll, means for actuating the work and work rest arcuately of the grinding throat, means for driving the regulating wheel and work rest actuating means in timed sequence, said means including an arm extending from the work rest, a Geneva wheel for engagement with the arm for actuating same intermittently, and a transmission line between the Geneva wheel and regulating member. 10
4. In a grinding machine of the class described for grinding tapered barrel shaped rolls the combination of a grinding wheel having an operative face conforming to the periphery of the roll to be ground, an opposed regulating member having a spiral track and contacting with the roll at two points of equal diameter for controlling the rotation of the rolls, the grinding wheel and regulating member being spaced from one another to form a grinding throat, a work rest within the grinding throat having an inclined seat extending downwardly toward the regulating member for receiving the roll, means for actuating the work and work rest arcuately of the grinding throat, means for driving the regulating wheel and work rest actuating means in timed sequence, said means including an arm extending from the work rest, a Geneva wheel for engagement with the arm for actuating same intermittently, and a transmission line between the Geneva wheel and regulating member. 15
5. In a grinding machine of the class described and regulating wheels forming a grinding throat therebetween, the operative opposed faces of the grinding and regulating wheels being substantially contragenerically formed and the grinding wheel having a concaved operative face and the regulating wheel having a spiral path conforming with the periphery of the work, a work rest blade arcuately shiftable through the throat in a plane substantially parallel to the contrageneric faces of the wheels, means for driving the said wheels at fast and slow speed to respectively effect a stock removal from the work and control its rotation, means driven from the regulating wheel for operating the work rest in timed relation with the rotation of the same, said means comprising a gear associated with the regulating wheel, a Geneva wheel intermittently oscillating the work rest blade in a given direction, and transmission gearing between the regulating wheel and Geneva wheel. 20
6. In a grinding machine of the class described the combination of a pair of opposed grinding and regulating wheels forming a grinding throat therebetween, the operative opposed faces of the grinding and regulating wheels being substantially contragenerically formed and the grinding wheel having a concaved operative face and the regulating wheel having a spiral path conforming with the periphery of the work, a work rest blade arcuately shiftable through the throat in a plane substantially parallel to the contrageneric faces of the wheels, means for driving the said wheels at fast and slow speed to respectively effect a stock removal from the work and control its rotation, means driven from the regulating wheel for operating the work rest in timed relation with the rotation of the same, said means comprising a gear associated with the regulating wheel, a Geneva wheel intermittently oscillating the work rest blade in a given direction, and transmission gearing between the regulating wheel and Geneva wheel. 25
7. In a grinding machine of the class described the combination of a pair of opposed grinding and regulating wheels forming a grinding throat therebetween, the operative opposed faces of the grinding and regulating wheels being substantially contragenerically formed and the grinding wheel having a concaved operative face and the regulating wheel having a spiral path conforming with the periphery of the work, a work rest blade arcuately shiftable through the throat in a plane substantially parallel to the contrageneric faces of the wheels, means for driving the said wheels at fast and slow speed to respectively effect a stock removal from the work and control its rotation, means driven from the regulating wheel for operating the work rest in timed relation with the rotation of the same, said means comprising a gear associated with the regulating wheel, a Geneva wheel intermittently oscillating the work rest blade in a given direction, and transmission gearing between the regulating wheel and Geneva wheel. 30
8. In a grinding machine of the class described the combination of a pair of opposed grinding and regulating wheels formed to the included contour of a formed work piece, the proximate points of said wheels being spaced from one another to provide an arcuate grinding throat extending in the direction of the axis of the wheels, a work support within said grinding throat and operable in an arcuate path parallel with the axis of the arcuate grinding throat from a loading position exteriorly of the throat, and means for automatically depositing work pieces onto the said support when in the loading position, said means including a chute for the work, and means at the end thereof normally preventing discharge of work pieces therefrom. 35
9. In a grinding machine for grinding formed work pieces the combination of a grinding wheel having a contour contrageneric to the contour to be produced on the work, a work support adjacent the grinding wheel for supporting the work piece, positive means for actuating the work support through a path parallel with the surface of the wheel while supporting the work in contact with the wheel the work support having an inclined supporting portion whereby the work is discharged by gravity therefrom after it passes the grinding wheel, yielding means for returning the work support to its initial position, means opposed to the grinding wheel of a contour sub- 40

stantially contrageneric to the operative face of the grinding wheel for frictional engagement with the work to control the rotation thereof, and an operative coupling between the friction control means and the positive means for actuating the work support whereby they are actuated in synchronism.

10. In a centerless grinder for grinding formed work pieces the combination of a pair of opposed grinding and regulating wheels forming a grinding throat conforming substantially to the contour of the work to be produced, a work rest blade having an inclined seat inclining in the direction of the operative face of the regulating wheel for 15 receiving and supporting a work piece, means pivotally mounting the work rest blade for oscillation through the grinding throat, positive means for oscillating said work rest blade in one direction, and yielding means for oscillating the blade in the 20 other direction.

11. In a centerless grinder for grinding formed work pieces the combination of a pair of opposed grinding and regulating wheels forming a grinding throat conforming substantially to the contour of the work to be produced, a work rest blade having an inclined seat inclining in the direction of the operative face of the regulating wheel for receiving and supporting a work piece, means pivotally mounting the work rest blade for oscillation 25 through the grinding throat, positive means for oscillating said work rest blade in one direction, and yielding means for oscillating the blade in the other direction, said positive means comprising a cam wheel having a plurality of operative portions 30 thereon spaced by a plurality of inoperative portions, and means associated with the work rest blade for engagement with said operative means of the cam wheel.

12. In a machine for grinding formed work 40 pieces such as tapered barrel rolls the combination of a grinding wheel having a concave operative surface, an opposed regulating wheel having a convex operative surface, the operative surfaces of the grinding and regulating wheels at 45 their proximate point forming an arcuate grinding throat, a work rest blade oscillatable in an ar-

cuate path through the grinding throat for positively feeding a work piece therethrough, means for positively actuating the blade in one direction, and means for yieldingly actuating the blade in the other direction.

13. In a machine for grinding formed work pieces such as tapered barrel rolls the combination of a grinding wheel having a concave operative surface, an opposed regulating wheel having a convex operative surface, the operative surfaces of the grinding and regulating wheels at their proximate point forming an arcuate grinding throat, a work rest blade oscillatable in an arcuate path through the grinding throat for positively feeding a work piece therethrough, 15 means for positively actuating the blade in one direction, means for yieldingly actuating the blade in the other direction, a magazine for unfinished work pieces at one end of the arcuate path of movement of the blade, and a discharge 20 chute at the other end of the arcuate path of movement of the blade for receiving finished work pieces therefrom.

14. In a machine for grinding formed work pieces such as tapered barrel rolls the combination of a grinding wheel having a concave operative surface, an opposed regulating wheel having a convex operative surface, the operative surfaces of the grinding and regulating wheels at their proximate point forming an arcuate grinding 25 throat, a work rest blade oscillatable in an arcuate path through the grinding throat for positively feeding a work piece therethrough, means for positively actuating the blade in one direction, means for yieldingly actuating the blade in the 30 other direction, a magazine for unfinished work pieces at one end of the arcuate path of movement of the blade, a discharge chute at the other end of the arcuate path of movement of the blade for receiving finished work pieces therefrom, 35 and means automatically actuated for releasing an unfinished piece from the magazine onto the work rest blade and operable when the work rest blade is aligned therewith.
